UNITED STATES PATENT OFFICE.

CHARLES BLEAKLEY, OF NEW YORK, N. Y.

PLATE-GLASS HOLDER.

Application filed May 26, 1928. Serial No. 280,771.

This invention relates to means adapted to be used for the purpose of holding or retaining panels or plates of glass in place on the top of and along the marginal edges of a service or display counter of the kind used in stores, said panels or plates of glass constituting a means or barrier which thwarts pilfering of articles of merchandise displayed on the top of the counter in full view.

10 An object of the invention is the provision of holders by means of which panels or plates of glass may be quickly and easily positioned in place on the top of and along the marginal edge or edges of a counter of the character mentioned, at a minimum of cost.

15 A further object of the invention is the provision of a set of holders which are so constructed that they may be readily attached to an upstanding marginal rim, flange, strip or the like on the top of a counter, to receive marginal edges of plates of glass, which are dropped or slid into place to be retained by the holders, assembled as may be desired, all around the marginal edge of the counter, or 20 at the front, or at the sides, or at both front and sides, or at the corner or corners only.

25 The nature of the invention and its distinguishing features and advantages will appear when the following specification is read 30 in connection with the accompanying drawing, in which—

35 Figure 1 is a plan view of a counter equipped with an assemblage of panels or plates of glass held in place by holders constructed in accordance with the invention.

40 Fig. 2 is a fragmentary sectional view, the section being taken on the line 2—2 of Fig. 1.

45 Fig. 3 is a perspective view of one of the corner holders.

Fig. 4 is a perspective view of an intermediate holder.

Fig. 5 is a top plan view showing an internal angle corner arrangement.

Fig. 6 is a perspective view of a left hand end holder, and

Fig. 7 is a perspective view of right hand end holder.

Referring now more particularly to the drawing, it will be apparent, that in Fig. 1 there is shown a counter 10 of the type used in stores on the top of which articles of merchandise are placed on display. The counter 10 is constructed of wood, and includes a top 11 and a framework 12 on which the top 11 is arranged. In accordance with the invention, pieces of wood in the form of molding

or beaded strips 13 are secured to the framework 12 so as to be disposed contiguous the marginal edges of the top 11 projecting a suitable distance upwardly with respect to 60 the upper surface of said top 11. In the present instance the strips 13 respectively are arranged contiguous the front and side edges of the top 11. For satisfactory results, the strips 13 may project about two inches above 65 the upper surface of the top 11. It will now be understood that there is provided along the marginal edges of the top 11 an upstanding rim or flange.

70 In accordance with another feature of the invention, use is made of a suitable number or set of holders among which are corner holders 14, intermediate holders 15, and left and right hand end holders 16. One of the corner holders 14 is shown most clearly in 75 Fig. 3 of the drawing, and consists of an upper panel margin receiving section or portion 17, and a lower attaching section, portion or end 18. The section or portion 17 is substantially L-shaped in general cross section, and has receiving channels 19 disposed at a right angle with respect to each other, or in other words, perpendicular to each other. Each channel 19 opens through the upper and lower ends of the section or portion 17. In the present instance the section or portion 17 is of hollow construction in that the channels 19 are connected by blocks 20 which form stops. The section or portion 17 80 may be made of solid construction throughout, if desired. Each channel 19 presents an inner flange 21 and an outer flange 22. The portion or end 18 is L-shaped in cross section 85 and is formed coincidental with the inner flanges 21. The said portion or end 18 is 90 provided with one or more holes, a single hole 23 being provided in the present instance for the accommodation of a suitable fastening element such as a screw. The portion or end 18 is adapted to be positioned in the entrance angle between the strips 13 at one corner of the top 11 of the counter, and is secured by one or more fastening elements, one of which is indicated in dotted lines in Fig. 2, indicated at 24, to the adjacent strip or strips 100 13. Thus the holder 14 will be vertically disposed, with the channels 19 disposed in the plane of the related strips 13. The lower edges of the outer flanges 22 will be in contact with the upper surface of the related 105 strips 13.

Each intermediate holder 15 consists of an

upper panel marginal receiving section or portion 25 and a lower attaching portion or end 26. The upper section or portion 25 may be H-shaped in cross section throughout, or 5 may be of hollow construction as shown in the present instance. The section or portion 25 has receiving channels 27 respectively at opposite sides. Each channel 27 presents inner flanges 28 and outer flanges 29. Blocks 30 10 connect the flanges 28 and 29 and constitute stops, it being understood that an equivalent construction may be obtained by having the section or portion 25 H-shaped throughout. The lower portion or end 26 is formed coincident 15 with the inner flanges 28, and is provided with holes 31 for the accommodation of suitable fastening elements such as screws. The portion or end 26 is brought against the inside face of one of the strips 13, the front 20 strip, in the present instance, and is secured thereto by the screws. Thus the holder 15 is secured in place vertically disposed with the channels 27 in the plane of the related strip 13 over the upper surface thereof with 25 the lower edge of the outer flanges 29 in contact with said upper surface.

Each end holder 16 consists of an upper panel margin receiving section or portion 32 and a lower attaching portion or end 33. 30 The upper section or portion 32 is of U-shape in cross section throughout which presents a channel 34 consisting of an inner flange 35, an outer flange 36, and a connecting web 37 which constitutes a stop. The portion or 35 end 33 is formed coincident with the inner flange 35 and is provided with holes 38 which accommodate screws. The holder 16 shown in Fig. 5 is of left hand construction, and it is to be understood that end holders of right 40 hand construction will also be provided. The lower portion or end 33 of the end holder 16 will be positioned against the inner face of the related strip 13, and will be secured thereto by screws respectively received by the holes 38. Thus the holder 15 will be vertically 45 disposed with the channel 34 in the plane of the related strip 13 above the upper surface thereof with the lower edge of the outer flange 36 in contact with the upper surface 50 of the related strip 13.

When it is desired to use my invention in connection with an internal angle of the marginal molding in case of L-shaped counters, the end holders, right and left, will 55 be employed, and they are juxtaposed to form a continuation of the panels on the inside of the L-shaped counters, and to accomplish this result, they occupy the position as shown in Figure 5, in other words, the panels will therefore be continuous along the molding of the entire outside and inside of the counter.

In the present instance, by way of example, there are shown two corner holders 14 respectively at two of the corners of the top 11 of 60 the counter, one intermediate holder 15 at the

front, and left and right hand holders 16 respectively at the opposite sides of the top 11 of the counter. The holders 14, 15 and 16 are spaced with respect to each other, and so positioned that panels or plates of glass 39 may 70 be assembled in angular relationship, the opposite side edges of the panels or plates of glass 39 respectively being received by the channels presented by the holders. Each of the plates of glass 39 at the front has the opposite side edges thereof received in channels 19 and 27 respectively of the corner holder 14 and intermediate holder 15. Each of the end plates of glass 39 has the opposite side edges respectively disposed in the channels 80 19 and 34 respectively of the related holders 14 and 16. The lower edges of the plates of glass 39 are in contact with the horizontal upper even surface presented by the strips 13. The plates of glass 39 used, will be of 85 uniform length, preferably 24 inches, and may be of any preferred height, it being understood, that the upper margin receiving sections of the holders may be of such dimensions as to correspond to the height of the 90 plates of glass 39. The holders are made of metal, preferably aluminum.

It is to be understood that panels or plates of glass may be assembled to extend all around the marginal edge of a counter top, or at the 95 front, or at the sides, or at both front and sides, or at one or more of the corners. Any suitable number and arrangement of holders may be employed to meet certain conditions, and after the holders are secured in place, the 100 panels or plates of glass 39 are merely dropped or slid into the channels presented by the holders; the said panels or plates of glass being readily removable for the purpose of cleaning the same.

105 I claim:

1. An open top counter having a marginal upstanding molding therearound, a plurality of integral straight panel holders attached 110 interiorly of said molding, each of said holders comprising a body portion resting on the upper edge of said molding, and a shank portion lying flat against and secured to said molding, the said body portions having grooves therein, and a plurality of readily detachable vertically extending panels 115 mounted in said grooves, and resting on top of said molding.

2. An open top counter having a marginal upstanding molding therearound, a plurality of integral straight panel holders attached 120 interiorly of said molding, each of said holders comprising a body portion resting on the upper edge of said molding and a shank portion lying flat against and secured to said molding, at least one of said holders having a lower shank portion, and an upper body portion provided with oppositely opening 125 grooves lying in the same plane, and a plurality of readily detachable vertically extend- 130

ing panels mounted in said grooves and resting on top of said molding.

3. An open top counter having a marginal upstanding molding therearound, a plurality of integral straight panel holders attached 5 interiorly of said molding, each of said holders comprising a body portion resting on the upper edge of said molding, and a shank portion lying flat against and secured to said molding, at least one of said holders having 10 a lower right angular shank member, and an upper body portion, said body portion being provided with right angular outwardly opening grooves, and a plurality of readily detachable vertically extending panels mounted 15 in said grooves and resting on top of said molding.

4. An open top counter having a marginal upstanding molding therearound, a plurality 20 of integral straight panel holders attached interiorly of said molding, each of said holders comprising a body portion resting on the upper edge of said molding, and a shank portion lying flat against and secured to said molding, at least one of said holders having 25 a lower flat shank portion and an upper body portion provided with a laterally outwardly opening groove, adapted to act as a terminal for the aforesaid panels, and a readily detachable vertically extending panel mounted 30 in said groove and resting on top of said molding.

5. An open top counter having a marginal upstanding molding therearound and a plurality of integral straight panel holders attached 35 interiorly of said molding, each of said holders comprising a body portion resting on the upper edge of said molding, and a shank portion lying flat against and secured to said molding, one of said holders having a lower 40 shank portion and an upper body portion with a lateral outwardly opening groove adapted to act as a terminal for said panels, and a second holder having a lower shank portion lying flat against and secured to the said 45 molding, and an upper body portion provided with a lateral outwardly opening groove, said groove opening in a direction opposite to that of the first mentioned holder, whereby the aforesaid holders may be 50 angularly disposed with respect to each other to constitute an internal angle for the purpose of continuation of the aforesaid panels, entirely around said counter, and a plurality of readily detachable vertically extending 55 panels mounted in the grooves of the aforesaid holders, and resting on top of said molding.

Signed at New York, in the county of New York and State of New York, this 25th day 60 of May A. D. nineteen hundred and twenty-eight.

CHARLES BLEAKLEY.
